UNITED STATES PATENT OFFICE.

AXEL C. V. MALM, OF LANSDOWNE, PENNSYLVANIA.

STEAM-PLATEN FOR PRESSES.

1,355,236.

Specification of Letters Patent. Patented Oct. 12, 1920.

Application filed December 22, 1919. Serial No. 346,562.

To all whom it may concern:

Be it known that I, AXEL C. V. MALM, a citizen of the United States, residing at Lansdowne, in the county of Delaware and State of Pennsylvania, have invented certain new and useful Improvements in Steam-Platens for Presses, of which the following is a specification, reference being had therein to the accompanying drawing.

10 This invention relates to steam platens for presses, such, for example, as the power presses commonly employed for curing rubber, bakelite and the like. One object of the invention is to provide a platen of this kind, 15 the surface of which may be quickly and uniformly heated by the application of steam to the interior thereof.

Another object of the invention is to provide such a device which will be so constructed that a cooling medium, such as 20 water, may be applied thereto immediately after the steam has been cut off, without distorting the platen or causing the same to leak or otherwise injuring the same. Other 25 objects of the invention will appear as the device is described in detail.

In the accompanying drawings Figure 1 is a side elevation of a press, showing my invention applied thereto; Fig. 2 is a trans- 30 verse sectional view of a portion of such a press taken on the line 2—2 of Fig. 1; Fig. 3 is a plan view of a platen embodying my invention; Fig. 4 is a transverse sectional view of the same; Fig. 5 is a plan view of 35 the inner face of one of the sections of such a platen; Fig. 6 is an edge view of the section of Fig. 5; Fig. 7 is a transverse sectional view taken on the line 7—7 of Fig. 5; Fig. 8 is a plan view of the inner surface of the 40 other section of the platen; and Fig. 9 is a transverse sectional view taken on the line 9—9 of the section of Fig. 8.

In these drawings I have illustrated one embodiment of my invention. I have shown 45 the same as applied to a power press of a well known construction but it will be understood that the invention may be applied to presses of various kinds and that it may take various forms, either for the purpose of 50 accommodating it to presses of this kind, or for other purposes.

The press here shown comprises a base 1 and a top plate 2 which is connected to the base by means of vertical rods 3. Mounted 55 on the base 1 is a ram comprising a head 4 and a plunger 5 mounted in a cylinder 6 in

the base 1, which may be operated by the application of steam or other fluid. Interposed between the ram and the top plate 2 are a series of platens or pressure plates 7 which are mounted for vertical movement 60 relatively one to the other and to the top plate so that when the material to be cured has been placed between the platens, and between the upper platen and the top plate 65 and the lower platen and the plunger, the upper movement of the ram will cause the several platens to be moved upwardly, one toward the other, and toward the top plate. The platens may be supported in any suitable manner but in the present construction I have provided each platen with a series of lugs, or ears 8, there being preferably one of these ears at each corner of the platen, which is here shown as square. Depending 70 from the top plate and rigidly secured thereto near the respective corners thereof are four rods, or hangers, 9, each of which extends through an opening in the adjacent lug 8, in the uppermost platen. Secured to each 75 lug of this uppermost platen, preferably by mounting the same in another opening therein, is a hanger, or rod, 10, which extends through an opening in the corresponding lug 8 of the next lower platen. The lugs 80 of this next lower platen are also provided with hangers, or rods, 11, which extend through openings in the lugs 8 of the lowermost platen, there being in the press here shown but three platens. It will be apparent 85 that each platen is free to move vertically on its hangers and that the hangers themselves will move vertically with the platens to which they are secured.

Each platen is provided with a chamber 90 within which steam may circulate and this chamber is so constructed and arranged that the steam will come in contact with relatively large portions of the upper and lower walls of the platen. It is, of course, necessary 95 that the platen shall be of a very strong, durable character and I prefer to make the same cast steel. To facilitate the manufacture thereof I prefer to form the same in two sections which may be placed 100 face to face and rigidly secured one to the other. Each section is provided in its face with channels, the channels of the two sections being so arranged that they will be 105 in communication one with the other and that the greater portions of the inner surfaces of both sections will be exposed di-

rectly to the steam in the channels of one, or both, of the sections, and further, the arrangement is such that those portions of the surfaces which are not exposed directly to the steam will be relatively small and will be surrounded by portions which are in contact with the steam. The platen may be of any suitable shape and the sections may take various forms. In the present construction the platen is substantially square and the sections are flat. Two sections in the present instance are very similar in their construction and the lower section which is indicated by the reference numeral 12, carries the ears, 8, while the upper section, 13, does not have ears. As has been stated, the channels in the sections may take various forms, but in the present instance I have shown each section as having a channel 14 extending completely about the same near its outer edges. A series of substantially parallel channels 15 extend transversely to the section and communicate at their ends with the surrounding channel 14. When the two sections are assembled to form the platen the channels 15 of the one section extend transversely to the channels 15 of the other section so that the ribs 16, which separate the channels 15, will intersect and rest one upon the other. Because of the intersecting arrangement of the channels it will be apparent that the steam, or other fluid which may be caused to circulate therein, will come directly in contact with the channeled portions of both sections and with the inner surfaces of the ribs where they intersect the channels. The only portions of the surfaces which do not come in direct contact with the steam are those portions of the ribs which intersect and rest one upon the other, and these portions are surrounded by the channels. As a result of this construction the surfaces of the platen are very quickly and very uniformly heated. The two sections are rigidly secured one to the other preferably by means of a series of screws, 17, which extend through the ribs at their points of intersection, the ribs being preferably enlarged, as shown at 18, to provide ample support for the screws. The sections are further secured one to the other by welding their adjacent edges together, preferably by electrical welding. This welded joint is not only very strong and durable but it forms a perfectly steam tight joint between the two sections. Consequently the platen is of a very strong, durable construction and will not be injuriously affected by the injection of a cooling medium into the channels immediately after the steam is cut off and while the platen is still hot. The manner of connecting the two sections as well as the construction of the two sections is such that there will be little or no tendency

to warp or become distorted by the sudden changes in temperature and the wedged joints at the edges of the sections will not be liable to break and thus cause leakage. A further advantage of the welded joints is that it does away with all packing between the two sections. Not only is the platen as here constructed highly efficient and of a strong, durable character, but it can be readily and cheaply manufactured as the sections are each cast in one piece and very little machine work is required.

The platen may be provided with an inlet and an outlet of any suitable character and arrangement. In the present instance I have shown two ports, 19, leading through the edge of the platen and communicating with the outer channel 14. In the present arrangement the ports are both arranged in the same edge of the platen and are adapted to have steam pipes connected therewith. Preferably the outlet of one platen is connected with the inlet of the other so that the steam passes in series through the several platens. Obviously the top plate and the head 4 of the ram may be constructed in a similar manner and may, if desired, be connected in series with the platens.

While I have shown and described one embodiment of my invention, I wish it to be understood that I do not desire to be limited to the details thereof as various modifications may occur to a person skilled in the art.

Having now fully described my invention, what I claim as new and desire to secure by Letters Patent is:

1. A device of the character described comprising two sections placed face to face, rigidly connected one to the other and having channels in their adjacent faces so arranged that the channels in one section will communicate with the channels in the other section, and having inlet and outlet ports leading to and from the channels.

2. A device of the character described comprising two sections placed face to face and having channels in their adjacent faces so arranged that the channels in one section will communicate with the channels in the other section, and having inlet and outlet ports leading to and from said channels, said sections being connected one to the other to form steam tight joints at their edges.

3. A device of the character described comprising two sections placed face to face and having channels in their adjacent faces so arranged that the channels in one section will communicate with the channels in the other section, and having inlet and outlet ports leading to and from said channels, said sections being welded one to the other at their edges.

4. A device of the character described comprising two sections placed face to face,

- each section having substantially parallel channels and the channels of the two sections extending transversely one to the other, said device also having inlet and outlet ports 5 leading to and from said channels, and said sections being connected one to the other to form steam tight joints at their edges.
5. A device of the character described comprising two sections placed face to face, 10 rigidly connected one to the other and having channels in their adjacent faces, the channels in the one section being arranged to intersect the channels in the other section, said device also having inlet and outlet ports 15 leading to and from said channels.
6. A device of the character described comprising two sections placed face to face, rigidly secured one to the other and each having in its inner face a channel extending 20 about the same near the edges thereof and other channels extending across the same and communicating with the first mentioned channel, the last mentioned channels of one section intersecting the corresponding channels of the other section, and inlet and outlet ports leading to and from said channels. 25
7. A device of the character described comprising two flat sections of corresponding 30 shape placed face to face and each having in its inner face a channel extending entirely about the same near the outer edge thereof and other channels communicating at their ends with the first mentioned channel, the several channels of the one section 35 being arranged to communicate with the corresponding channels of the other section, and inlet and outlet ports leading to and from said channels, said sections being rigidly connected one to the other to form steam tight joints at their edges. 40
8. A device of the character described comprising two sections placed face to face and having channels in their adjacent faces 45 so arranged that the channels in one section
- will communicate with the channels in the other section and having inlet and outlet ports leading to and from said channels, said sections being welded one to the other at their edges, and fastening devices connecting intermediate portions of said sections one to the other. 60
9. A device of the character described comprising two sections placed face to face and each having in its inner face a channel 65 extending about the same near the edges thereof, and substantially parallel channels communicating at their opposite ends with the first mentioned channel, the last mentioned channels of the one section extending 70 transversely to the channels of the other, and inlet and outlet ports leading to and from said channels, said sections being welded one to the other along their edges. 75
10. A device of the character described comprising two sections placed face to face, each section having in its inner face a channel extending about the same near the edge thereof, and having transverse channels 80 communicating at their ends with the first mentioned channel and separated by ribs and the ribs of the two sections intersecting and resting one upon the other, said sections being connected one to the other to form steam tight joints at their edges. 85
11. A device of the character described comprising two sections placed face to face, each section having in its inner face a channel extending about the same near the edge thereof, and having transverse channels 80 communicating at their ends with the first mentioned channel and separated by ribs, the ribs of the two sections intersecting and resting one upon the other, and fastening devices extending through intersecting portions of said ribs. 85

In testimony whereof I affix my signature
hereunto.

AXEL C. V. MALM.
